COMBINED CLOCK, PICTURE FRAME AND SUPPORT FOR A PORTABLE RADIO OR THE LIKE

Zoltan B. Tokar, 419 E. 93rd St.,
New York, N.Y. 10028

Filed July 17, 1967, Ser. No. 7,830

Term of patent 3½ years

(Cl. D42—7)

Fig. 1.

Fig. 2.

Fig. 3.

Fig. 4.

FIG. 1 is a top plan view of a combined clock, picture frame and support for a portable radio or the like, showing my new design;

FIG. 2 is a front elevational view;

FIG. 3 is a right side elevational view;

FIG. 4 is a rear elevational view; and

FIG. 5 is a rear perspective view.

The picture and portable radio shown in broken lines are for illustrative purposes only.

I claim:

The ornamental design for a combined clock, picture frame and support for a portable radio or the like, substantially as shown and described.
